TABLET DISPENSER

Samuel Tapper, 440 Baldwin Road, Maplewood, N.J.

Filed Sept. 4, 1959, Ser. No. 57,428

Term of patent 14 years

(Cl. D52—2)

Fig. 1

Fig. 2

Fig. 3

Fig. 4

Fig. 1 is a top plan view of a tablet dispenser, showing my new design;

Fig. 2 is a side elevational view thereof, taken partly in section;

Fig. 3 is a perspective view thereof, as seen from below; and

Fig. 4 is a perspective view thereof without the cover, as seen from above.

I claim:

The ornamental design for a tablet dispenser, as shown.
